CLAIM

The ornamental design for a tire tread, as shown and described.

DESCRIPTION

FIG. 1 is a front view of a tire tread showing our new design; FIG. 2 is an enlarged, partial front view of the tire tread shown in FIG. 1;

FIG. 3 is an enlarged, partial front view taken generally from the front and top of the tire tread shown in FIG. 1;

FIG. 4 is an enlarged, partial perspective view generally taken from the front and a first side of the tire tread shown in FIG. 1;

FIG. 5 is a perspective view of the tire tread shown in FIG. 1;

FIG. 6 is a side view of the tire tread shown in FIG. 1; and, FIG. 7 is an enlarged, side view of the tire tread shown in FIG. 6.

The dash-dot-dash lines shown in the Figures illustrate an unclaimed boundary line and form no part of the claimed design.
